CLAIM

The ornamental design for a lamp connector as shown and described.

DESCRIPTION

FIG. 1 is a front, left and bottom perspective view of a lamp connector, showing our new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view of the lamp connector shown in an environmental state.

The dashed broken lines in FIGS. 1-8 depict portions of the lamp connector that form no part of the claimed design. The dashed broken lines shown in FIG. 9 depict environmental structures and form no part of the claimed design.

1 Claim, 9 Drawing Sheets
